UNITED STATES PATENT OFFICE.

JAMES TURNER FLIPPEN, OF WIER, TENNESSEE.

HINGE.

SPECIFICATION forming part of Letters Patent No. 725,433, dated April 14, 1903.

Application filed June 10, 1902. Serial No. 111,041. (No model.)

To all whom it may concern:

Be it known that I, JAMES TURNER FLIPPEN, a citizen of the United States, residing at Wier, in the county of Wilson and State of Tennessee, have invented new and useful Improvements in Hinges, of which the following is a specification.

This invention relates to hinges; and the primary object thereof is to produce a device of this character especially adapted for use in connection with gates to gradually raise the gate in a vertical plane while the same is being opened, whereby any inequalities of the ground in the path of the gate are compensated for, and to overcome any sagging in the gate to permit it to be freely turned upon its hinges.

A further object of the invention is to produce a hinge which is cheap, durable, and efficient.

Still further objects of the invention will appear as the nature of the same is more fully understood from the following description and claims, taken in connection with the accompanying drawings.

The invention consists in the construction, combination, and arrangement of parts hereinafter fully described and claimed.

In the drawings, Figure 1 is a side elevation of a gate equipped with hinges embodying my invention. Fig. 2 is a perspective view of the hinge. Fig. 3 is a detail perspective view of a portion of the hinge involving a slight modification. Fig. 4 is a central longitudinal section of Fig. 3. Fig. 5 is a central longitudinal section of Fig. 2, the movable member being broken away.

1 designates a post or standard to which a gate 2 is hinged, and 3 a latch-post adapted to be engaged by a latch 4 to secure the gate in closed position.

5 designates the stationary member of the hinge and comprises the several elements hereinafter fully described.

45 6 designates a securing-bolt having one end thereof screw-threaded to secure the member in applied position on the post 1, and the opposite end thereof is provided with a perforation 7 for the reception of a vertically-disposed pintle 8. The pintle has intermediate its ends an annular recess 9 for the reception of the wall of a perforation 10 in a base-plate

11 of the elevating means. The opposite end of the pintle is screw-threaded to adapt it to receive a nut 12 to secure the pintle upon the 55 securing-bolt and also to bind the base-plate 11 thereon by the upper shoulder of the recess 9 engaging the contiguous surface of the base-plate 11, as is obvious. The base-plate 11 has secured thereto a segmental flange 60 13, having the upper edge thereof gradually inclined from the ends of the segment to place the highest point of the incline in longitudinal alinement with the pintle 8 and at which point the flange is provided with a depression 14, forming a stop, the purpose of which will be hereinafter fully explained.

15 15 designates the movable member of the hinge and comprises a bar having one end thereof provided with a plurality of perforations 16, through which pass fastening means to secure the member in applied position upon the gate 2. The opposite end of said bar is horizontally disposed and provided with a bearing for the reception of the pintle 8, 70 75 hingedly connecting the two members. The bar is bent upon itself intermediate its ends to form a casing 17, having walls thereof provided with alining bearings in which is journaled a shaft carrying a grooved roller 18, 80 adapted to ride upon the inclined edge of the flange 13 when the gate is turned upon its hinges.

It is apparent from the above description, taken in connection with the accompanying 85 drawings, that a gate equipped with hinges of my improved construction will, when turned upon its hinges through the medium of the inclined edge of the flange and the grooved roller, gradually be elevated and when the 90 roller engages the stop 14 will be held in its opened position.

In the modified form disclosed in Figs. 3 and 4 of the drawings I have departed from the form above described by only making a 95 slight variation in the flange 13. The flange in this instance adapts the hinge for use in connection with gates that may be swung in either direction to open the same, and it consists of a segmental flange having the upper 100 edge thereof inclined to place the highest points of the inclination at the ends of the segment. The highest points of the inclination are provided with grooves 19, forming

stops in horizontal alinement with the pintle 8, and the lowest point of the inclination is provided with a stop 20.

It will be perceived from the above description of the modified form of the flange that a gate equipped with hinges provided with a flange of this particular construction may be swung in either direction to open the same and that while being turned upon its hinges will be gradually elevated and held in its opened position by the roller engaging one of the stops 19. The stop 20 when engaged by the roller will hold the gate in its closed position, thereby obviating the necessity of a latch.

15 The roller in view of its grooved construction will remain in constant engaged relation to the flange irrespective of any tendency of the two members of the hinge working loose as a consequence of the wearing of 20 one member which engages the pintle of the other member.

The construction of the base-plate and flange renders it possible to convert any strap-hinge having a vertically-disposed pintle into a hinge of the character above described by securing the base-plate upon the pintle, and in such instances it is not absolutely necessary to the working of the hinge to provide the movable member with a roller.

30 It is obvious from the above description, taken in connection with the accompanying drawings, that I provide a hinge which will compensate for the sagging of a gate and for any inequalities of the ground adjacent the 35 lower edge thereof and which will also hold the gate either in its closed or opened position.

It may be further stated that by reason of the inclinations of the flanges the gate will 40 automatically return to its closed position if the same has not been opened a sufficient distance to place the rollers 18 in engagement

with the stops 19 and that when the rollers are in engagement with the stops 19 the gate may be automatically closed by withdrawing 45 the rollers from such engagement.

Having thus fully described the invention, what is claimed as new is—

1. A hinge comprising a securing-bolt, a base-plate having a perforation and provided 50 with a vertical flange having an inclined edge, a pintle having one end thereof reduced to provide a shoulder and adapted to extend through the perforation to permit the shoulder to lie upon the base-plate, means carried 55 by the pintle to engage the under side of the securing-bolt to clamp the shoulder against the base-plate, thereby detachably securing the pintle and base-plate in applied position, and a movable member adapted to have a 60 pivotal connection with the pintle to permit of its riding upon the vertical flange.

2. A hinge comprising a stationary member, a base-plate provided with a flange, means for detachably securing the base-plate 65 to the member, a movable member, and means for connecting the movable member to the stationary member to permit of its co-operating with the flange.

3. A hinge comprising a securing-bolt, a 70 base-plate provided with a vertical flange having an inclined edge, a pintle detachably secured to the stationary member and also adapted to secure the base-plate in applied position, and a movable member adapted to 75 have a pivotal connection with the pintle to permit of its riding upon the vertical flange.

In testimony whereof I affix my signature in presence of two witnesses.

JAMES TURNER FLIPPEN.
